UNITED STATES PATENT OFFICE.

ARTHUR ZITSCHER AND ROBERT SCHMITT, OF OFFENBACH-ON-THE-MAIN, GERMANY,
ASSIGNORS TO CHEMISCHE FABRIK GRIESHEIM-ELEKTRON, OF FRANKFORT-ON-THE-MAIN, GERMANY, A CORPORATION.

DI-ACYLAACETYL-DIAMINO COMPOUNDS OF THE AROMATIC SERIES AND PROCESS
OF MAKING SAME.

No Drawing.

Application filed May 15, 1923. Serial No. 639,214.

To all whom it may concern:

Be it known that we, ARTHUR ZITSCHER and ROBERT SCHMITT, both citizens of the German Empire, and residents of Offenbach-on-the-Main, Germany, have invented certain new and useful Improvements in Di-Acylacetyl-Diamino Compounds of the Aromatic Series and Processes of Making Same, of which the following is a specification.

10 Our invention relates to new di-acylacetyl-diamino compounds of the general formula:

15 wherein R and R' represent the same or different aryl residues, Y any radicle of the hydrocarbon series containing at least one and not more than six carbon atoms, X a connecting link of the character explained hereinafter.

20 Under the definition given for Y we include aliphatic as well as aromatic radicles, under the term "connecting link" for X atoms and atom complexes such as O, S, $-\text{CH}_2-$, $-\text{CO}-$, $-\text{NH}-$, $-\text{NH.CO}-$, $-\text{N}=\text{N}-$,

25 and the like, which in our present invention form a connection between the two aryl residues, as indicated by the general formula given above.

The process of making the new compounds consists in heating acylacetic acid

30 esters, such as acetoacetic acid ester or its homologues or analogues, with the corresponding diamins, such as e. g. thioanilin, diaminodiphenylether, diaminoditolymethan, diaminobenzophenon, diaminodiphenylamin, aminobenzoylphenylenediamin, diaminooazobenzene, diaminooazoxybenzene, diaminodiphenylurea, aminophenoethylene ether and others, preferably in a solvent or diluent.

35 The new di-acylacetyl-diamino compounds may be used as primary products for the 40 production of dyestuffs.

45 The following examples illustrate the invention, the parts being by weight, and all temperatures in centigrade degrees.

Example 1.

50 Into a mixture, heated to 175-180°, of 205 parts of acetoacetic acid ester and 200 parts of nitrobenzene 76 parts of 4,4'-diaminobenzophenon are poured while stirring. The 55 mixture is held at 170-180°, until the reaction is finished. The pulp of crystals, formed after cooling down, is filtered, freed of nitrobenzene by means of ether and dried. The di-acetoacetyl-4,4'-diaminobenzophenon, 60 obtained in a yield of 68 p. c. of the theoretical yield, is crystallized from much water in colorless lustrous needles, melting at 175-176° C. (not corrected) with a feeble decomposition. The formula of this product is

Example 2.

70 A solution of 85 parts of 4,4'-diaminoazobenzene in 300 parts of acetoacetic acid ester is poured in 400 parts of boiling acetoacetic acid ester, kept boiling, until the splitting off of alcohol is finished, and the product of the reaction is worked up in the

75 usual manner. 116 parts of di-acetoacetyl-4,4'-diaminoazobenzene, that is 76 p. c. of the theoretical yield, are obtained. Crystallized from dilute acetic acid it forms an orange-yellow crystalline powder, decomposing at 233-234° (not corrected). The product obtained in this example has the formula

This product is one of a group corresponding to the general formula

85 where R and R' mean the same or different

80 aryl residues, Z one of a group of connecting links comprising $-\text{N}=\text{N}-$, $\text{O} \begin{array}{c} \text{N} \\ \backslash \\ \text{---} \text{N} \end{array}$, and $\text{N} \begin{array}{c} \text{---} \text{N} \\ \backslash \\ \text{O} \end{array}$

85 Y any radicle of the hydrocarbon series con-
